SURVEYOR'S COMPASS

Frederick Leupold, Portland, Oreg., assignor to
Leupold, Volpel and Company, Portland,
Oreg.

Application December 20, 1932
Serial No. 648,059

4 Claims. (Cl. 33—69)

My invention relates to surveyors' compasses in which the leveling tubes and other necessary or important parts are inclosed in a water-tight box; in which the rim of the enclosing ring is 5 lower than the surface of the cover-glass; in which horizontal cross-wires are stationarily attached to the front sight; and in which graduated scales are removably attached to the rear sight.

10 The objects of my invention are to manufacture a surveyor's compass which can conveniently be carried in a coat pocket; which cannot collect water on the covering glass, which prevents water from entering the inside of the compass box; 15 which protects the leveling tubes, the graduated circle, and the index, from the influx of water or from tampering, or accidental damage; which permits adjustment of the graduated circle for magnetic variations; and which permits the 20 reading of horizontal, as well as vertical angles.

Other objects and advantages are to be found in the construction and arrangement of parts as will be described in the specification and particularly pointed out in the appended claims.

25 I attain these objects with the mechanism illustrated in the accompanying drawing, in which:

Fig. 1 is a plan view of the entire apparatus.

Fig. 2 is a side view of Fig. 1.

Fig. 3 is an elevation of the rear sight.

30 Fig. 4 is an elevation of the front sight.

Fig. 5 is an elevation of the index bracket in the compass box.

Fig. 6 is a section through Fig. 5 along the line 6—6.

35 Similar numerals refer to similar parts throughout the several views.

My compass consists of a box 1, with an ear 2 for the front sight, and an ear 3 for the rear sight, integrally attached thereto. A straight edge 4 40 at one side of the box 1, and parallel to the ears 2 and 3, may be used for measuring or for drawing. The two leveling tubes 5—5 are placed in the bottom of the box 1, where they are protected from breakage or tampering. The magnetic 45 needle 6 is poised in the center of the box 1 and is provided with the customary needle-lifter 7. The housing 8 at the outside of the compass box 1, which is entered by the short arm of the needle-lifter 7, and which is provided with the lifting

50 screw 9, is cast integrally with the compass box 1, so that no opening or crevice is left whereby water may enter. In the outer circumference of the box 1 is turned an annular seat 10 for the reception of a ring 11, which latter rotates 55 with a water-tight fit in the seat 10. Radially

directed guide screws 12, in the ring 11, enter an annular groove 13 in the seat 10 and prevent accidental removal of the ring 11, without impeding rotation of the latter. The inner wall surface of the ring 11, above the compass box 1, has an annular shoulder 14 to the bottom of which is securely affixed a graduated circle 15, designating the cardinal points. A relatively heavy glass cover 16 is let into the ring 11 on top of the annular shoulder 14, and attached with water-proof cement. The upper surface of the glass cover 16 should be higher than the rim of the ring 11, so that no rain water can accumulate on top of the glass cover 16. An index bracket 17, Figs. 5 and 6, firmly secured to the bottom of the compass box 1, carries an index 18 in the precise line of sight, and readable in conjunction with the graduated circle 15, to adjust the latter for magnetic variations of the needle 6.

Hingedly attached to the front ear 2 of the 75 compass box 1 is the front sight 19 with the customary vertical cross-wire 20. A loop 21, at one side of the front sight 19, and near the bottom thereof, carries a horizontal cross-wire 22. A similar loop 23, at the other side of the front sight 80 19, and near the top thereof, carries the horizontal cross-wire 24.

Also hingedly attached, but to the rear ear 3 of the compass box 1, is the rear sight 25, with the customary vertical slit 26. On one side of 85 the slit 26, and held to the rear sight 25 by means of the screws 27, is a graduated scale 28, whose zero point is level with the horizontal cross-wire 22 on the front sight 19. Minus readings are taken toward the top of this scale 28. On the other side of the slit 26, and held in place by the screws 29, is a similar graduated scale 30, whose zero point, however, is level with the horizontal cross-wire 24 on the front sight 19, from which zero point plus readings are taken toward the 95 bottom. The scales 28 and 30 may be graduated in degrees or percentages of slope to suit the convenience of the operator, and, by removal of the screws 27 and 29, an exchange of scales may be easily effected.

It is, of course, to be understood that the graduations on the scales 28 and 30 must be accurately proportioned to the distance between the two sights 19 and 25.

The two sights 19 and 25, when not in use, may 105 be folded in as indicated by the dotted lines in Fig. 2.

In operation this apparatus is mounted on a tripod or Jacobs staff, as indicated by the numeral 31 in Fig. 2, the two sights are raised, the gradu-

ated circle is adjusted for magnetic variations, the compass is leveled off, and, if bearings are required, the latter are read by means of the vertical slit and cross-wire; if vertical angles are required, the readings are taken by the proper scale and the appertaining horizontal cross-wire.

Having thus described my invention, it will be seen that my objects have been accomplished, and though I have shown the preferred form of construction, I reserve to myself the right to make minor changes providing I do not contravene the spirit and principle of my invention.

I claim:

1. In a surveyor's compass, the combination of a compass box, a ring closely fitting and rotatably mounted on the box, a graduated circle, having cardinal points, firmly secured in the ring, a glass cover cemented in the ring above the graduated circle whereby to form a closed casing, the upper surface of the glass being higher than the rim of the encircling ring, leveling tubes on the bottom of the box, an index on the bottom of the box readable in conjunction with the graduated circle to adjust said graduated circle for magnetic variations, with means foldably attached to the compass box to measure horizontal and vertical angles.
2. In a surveyor's compass, the combination of a compass box, a front ear integrally attached to the compass box, a rear ear integrally attached to the diametrically opposite side of the com-

pass box, a housing cast integrally with the outer circumference of the compass box, a lifting screw mounted in the housing, a needle-lifter entering the housing from the inside of the compass box and terminating under the lifting screw, a straight edge at one side of the compass box and parallel with the ears, with means foldably attached to the ears to measure horizontal and vertical angles.

3. In a surveyor's compass, the combination of a water-tight compass, a front sight hingedly attached to the compass, a rear sight hingedly attached to the compass, horizontal cross-wires extending from each side of the front sight, and graduated scales removably attached to the sides of the rear sight, said graduated scales, in conjunction with the horizontal cross-wires, indicating vertical angles.

4. In a surveyor's compass, the combination of a water-tight compass, a front sight hingedly attached to the compass, a rear sight hingedly attached to the compass, a bottom loop attached to one side of the front sight, a horizontal cross-wire in said bottom loop, a top loop at the opposite side of the front sight, a horizontal cross-wire in said top loop, a graduated scale removably attached to each side of the rear sight, the zero point on each graduated scale being level with the corresponding horizontal cross-wire on the front sight.

FREDERICK LEUPOLD.
